J. H. HEUE

DOOR AND WINDOW BUCK

Filed Dec. 15, 1921

UNITED STATES PATENT OFFICE.

JOSEPH H. HEUE, OF CARROLL, IOWA.

DOOR AND WINDOW BUCK.

Application filed December 15, 1921. Serial No. 522,464.

To all whom it may concern:

Be it known that I, JOSEPH H. HEUE, a citizen of the United States, residing at Carroll, in the county of Carroll and State of 5 Iowa, have invented new and useful Improvements in Door and Window Bucks, of which the following is a specification.

This invention relates to devices for securing door and window frames in position 10 in a brick, hollow tile, stone, concrete, or any similarly constructed wall, such a device being known commercially as a door or window buck.

The object is to provide a simply constructed device, preferably formed by stamping from suitable sheet metal, two coacting members, one to be secured at the proper point on the outer face of the door or window frame and the other to be embedded in 20 the wall to be adjustably engaged with the first member to securely hold the frame in position.

Another object is to provide such a device as may be easily and quickly attached 25 to the frame and wall respectively without any necessity for nicety of adjustment or positioning during the process of building the wall, the two parts being brought into coacting relation when the wall reaches the 30 necessary height.

A full and complete understanding of the invention may be obtained from a consideration of the following detailed description, taken in connection with the accompanying 35 drawing forming a part of this specification, it being understood that while the drawing shows a practical form of the invention, the latter is not to be confined to strict conformity therewith, but may be 40 changed or modified so long as such changes or modifications mark no material departure from the salient features of the invention, as specifically pointed out in the appended claims.

45 In the drawing, in which similar reference characters designate corresponding parts throughout the several figures:

Figure 1 is a perspective view of the door or window buck;

50 Figure 2 is a plan view thereof;

Figure 3 is a front elevation of the upper portion of a door frame on a reduced scale, and showing the manner of securing the same in position in a wall by the improved devices;

Figure 4 is an enlarged detail vertical sectional view showing the manner of attaching the device to the frame and wall:

In the construction of concrete, hollow tile, brick, stone or other similar walls, difficulty is encountered in securing the frames of doors, windows, etc. in position and preventing any relative movement of the same, the use of nails, screws or the like being, of course, precluded, and it is for the purpose of overcoming such difficulty that the present device is intended.

The invention comprises two members one of which is in the form of an attaching plate adapted to be secured to the outer side faces 70 of the vertical members of a door or window frame, and as many of such attaching plates as are deemed necessary may be secured on each side member in longitudinal alinement with the same, and in a vertical line to coincide with the vertical center line of the wall being built. These attaching plates are preferably secured in their proper positions on the frame before the same is placed in position in the wall.

The other member of the device is L-shaped in form, one arm or wing of which is adapted to be placed between the courses of the brick or other masonry of which the wall is being built when the latter has 80 reached the proper height to register with the aforesaid attaching plate, and having its other arm or wing connected to the latter plate so that the frame is rigidly held in place, this last-named member of the device 85 constituting what may be called a mortar lock.

Referring to the drawing, there is shown an attaching plate 1 comprising an elongated strip of sheet steel or other suitable 95 metal formed by the simple process of stamping from ordinary stock material, the said plate being considerably longer than wide and having, adjacent to its ends, centrally located openings 2 countersunk on 100 one face for the reception of fastening screws 3, as clearly illustrated in Figure 4 of the drawing, said screws serving to hold the plate 1 to the outer side face of the vertically disposed side members 4 of a door or 105 window frame.

When the device is used in connection with metallic frames, the attaching strip is secured thereto by means of rivets and the said plates, in either case, are held by the fasten- 110

ers in longitudinal alinement, parallel with the front and rear edges of the frame members and preferably midway between the same, and any desired distance apart and 5 from the top and bottom of said side members.

The long, vertical side edges of the plate are provided with inwardly directed, V-shaped grooves 5 extending from top to bottom of the same, for a purpose to be explained.

The other member of the device, or mortar lock 6 is formed in a similar manner of the same kind of material, and comprises a 15 horizontally-disposed base plate 7 having its central portion cut or stamped out, as at 8, in any desired shape, to provide an opening for the passage of the mortar or cement being used in the construction of the wall in which 20 the door or window frame is to be held. At one end the base plate 7 is provided with perpendicularly disposed arms or extensions 9, whose outer edges are continuations of the side edges of the base plate 7, and whose inner, opposed edges, are beveled on the front and rear to provide V-shaped projections 10.

The space between the arms or extensions 9 is the same as the width of the aforesaid attaching plate 1, and the upper and lower 30 ends of the V-shaped projections 10 are slightly rounded, as at 11, so that the arm 9 of the mortar lock may be readily slid in a vertical direction, either upwardly or downwardly, into straddling relation to the attaching plate, with the grooves 5 of the latter receiving the projections 10 of the arms and rigidly holding the two members in adjusted relation to each other, there being no 35 possibility of any lateral displacement, while the two members may be readily moved upon each other in a vertical direction. By rounding the upper and lower corners of the inner edges of the arms 9, it will be seen that the introduction of the one member upon the other is greatly facilitated.

While the mortar lock 6 has been illustrated in the drawing with the arm 9 extending upwardly, it will be understood that the latter may be directed downwardly with equal 50 advantage, as the said arms are of equal thickness with the attaching plate 1 and are considerably less in length than the same.

As before stated, no especial care need be exercised in applying the plates 1 to the frame members 4, except that they shall be screwed into longitudinal alinement therewith. When the wall has been started, after the frame has been placed in position and 55 temporarily braced in the ordinary manner, the courses of brick or other material are laid in the usual way until the height of the lowermost attaching plate 1 has been reached, when the mason or builder places a mortar lock 6 into position, by sliding the arms, 60 which may extend either upwardly or down-

wardly, onto the said attaching plate and moving the same downwardly thereon until the base plate 7 rests firmly upon the upper surface of the top course of brick or other material. The usual layer of mortar or cement is then spread along on the top of the latter which fills in the opening 8 in the base plate of the mortar lock and firmly embeds the same and holds it firmly in locked engagement with the wall after the several 70 courses following have been laid. This same operation takes place when the next higher attaching plate 1 is reached, and it will be seen that the arms 9 may be located at or near either the top or the bottom of the attaching plate 1 when the desired locking engagement will be secured. Thus it will be understood that no especial nicety is required in placing the plates 1 in position on the frame initially, except that they be properly disposed to freely slide between the arms 9 75 of the mortar lock, as has been hereinbefore stated.

From the foregoing it will be seen that an extremely simple and cheaply constructed door or window buck has been provided, which may be easily applied to the frame and the wall in a manner to properly coat to hold the said frame in position, whether the latter be of wooden or metallic construction, and that the same is hidden from view when the wall is finished.

What is claimed is:—

1. A device of the class described, an attaching plate adapted to be secured to the outer faces of the side members of a door or window frame in longitudinal alinement therewith, in combination with a lock plate adapted to be embedded in the mortar between the courses of brick or other material of the wall having the frame, said lock plate having a pair of perpendicularly disposed arms at one end spaced apart a distance to receive the attaching plate between the same, whereby said plates are secured together 100 against lateral movement.

2. A device of the class described, an attaching plate adapted to be secured to the outer faces of the side members of a door or window frame in longitudinal alinement therewith and having its opposite, vertical side edges grooved, in combination with a lock plate adapted to be embedded in the mortar between the courses of brick or other material of the wall having the frame, said lock plate having an opening to receive the mortar and a pair of perpendicularly disposed arms at one end spaced apart a distance to receive the attaching plate between the same and having their inner opposed edges shaped to fit the grooves of said plate to prevent their lateral separation and to permit relative movement of the same lengthwise of the attaching plate.

3. A door or window buck comprising a

pair of coating members, one member being in the form of an elongated plate adapted to be secured longitudinally of the side member of a door or window frame and on the outer face thereof and having its long vertical, side edges provided with V-shape grooves extending from top to bottom thereof, the other member comprising a base plate provided with an opening and adapted to be anchored in the mortar or cement between the bricks or other material forming the wall having the said frame, the said base plate having at one end, a pair of arms arranged at right angles thereto and adapted to be located between the said frame and the adjacent wall and in flanking relation to the attaching plate on the frame, and

said arms having their inner opposed edges shaped to fit the V-shape groove of the plate to hold the frame in position.

4. In a device of the character described, the combination with an attaching plate and means for securing the same to a window or door frame, of a lock plate having means by which the same may be anchored in the wall of a building, and means for connecting the two plates for relative sliding movement longitudinally of the first-mentioned plate.

In testimony, that I claim the foregoing as my own, I have hereto affixed my signature.

JOSEPH H. HEUE.
